UNITED STATES PATENT OFFICE.

LEONARD M. WOODCOCK, OF AUBURN, NEW YORK.

FURNACE-GRAVE.

SPECIFICATION forming part of Letters Patent No. 359,120, dated March 8, 1887.

Application filed October 5, 1885. Serial No. 179,002. (No model.)

To all whom it may concern:

Be it known that I, LEONARD M. WOODCOCK, of the city of Auburn, New York, have invented certain new and useful Improvements 5 in Furnace-Grates, of which the following is a full and exact description, reference being had to the accompanying drawings, forming part of this specification, in which—

Figure 1 is a plan or top view; Fig. 2, a side 10 elevation; Fig. 3, a supporting-bracket; Fig. 4, a front view of lock; Fig. 5, an actuating-bar; Fig. 6, one of the sections, and Fig. 7, an end view of two section. Fig. 8, 9, 10, 11, and 12 are detail drawings to further illustrate the 15 locking mechanism.

In the drawings, F F' are the two supporting-plates or bed-pieces. The front one, F, has a lengthwise channel, t t, upon its upper surface, which retains the heads of the binding-bolts of the frame, and thereby causes all 20 movement of the grate from expansion to be from front to rear, the frame sliding upon the plate F'.

A A' B B' B² is the frame, which may be in 25 one or more divisions, as shown in the drawings. The lengthwise bars of this frame B B' B² are provided with air-holes S S S, as shown in Figs. 1 and 2, to increase the draft-area of the grate. The bars A A' are supplied with lugs 30 a, like those of the sections C. Within the frame the sections C are supported upon their terminal journals. These sections are each provided with a series of double lugs or projections, p p, Figs. 6 and 7. These lugs are of 35 peculiar form, extending upward above the axial bar o o, Fig. 6, whereby an air-space is obtained throughout their entire transverse length between each pair of lugs, or the whole distance r r², Fig. 7. Each lug is of the shape 40 shown in Fig. 7, the side r² r³ being approximately a circular arc from the center r, and the side r r' being of the same form from r² as a center. The upper or bearing surface, r r², is preferably flat, although this is immaterial, 45 while the bottom, also preferably flat, may be of any desired form consistent with economy of construction.

When two sections constructed as above described are simultaneously rocked upon their 50 terminal journals, as shown in Fig. 7, their opposed points remain throughout the move-

ment at an invariable distance apart for the amount of rocking shown in Fig. 7 by dotted lines. Therefore this grate will not break, 55 grind, or crush the coal in process of shaking.

A rocking movement of greater extent than shown by dotted lines in Fig. 7 will dump the grate.

The sections C have each a down-hanging arm, d, and by means of a bar, E, constructed 60 as shown, the sections are all made to rock in parallel position.

Motion is imparted to the grate-sections by means of the actuating-bar L, the hanging pivoted arm K, rod H, and tie-rod E. The rod 65 L is detachable, and when used is seated in a recess, h, in the hanging arm K, and being turned its projection l takes behind the lug n, thus retaining it in position. A hanger, G, is 70 secured to the front bed-plate, F, and is detachable therefrom by running back the screw w, Fig. 3, when the hanger may be drawn forward and disengaged from the lug u of the plate F. This hanger consists of a body portion 75 G, by which it is attached to the bed-plate F, and two strong parallel horizontal legs, g g, which extend to the front and are provided with bolt-holes to receive a bolt, g', which secures to the adjusted position upon the legs g g the hanging pivoted arm K, which 80 swings from front to rear between the legs g g. Said bolt also secures the lock-plate N, which is suspended rigidly from the legs g g. This casting N is of equal width with the lower 85 part of the pivoted arm K, which swings before it.

To the back of the casting N is pivoted the lock M, which consists of a pawl provided with a flange, m, at its lower end projecting each side of the lock-plate N and beyond said 90 plate to embrace and hold the pivoted arm K. The weight of this lock M is so disposed that when hanging free from its point of suspension it swings by gravity into contact with and does so embrace the arm K, and thus 95 serves to lock the said arm K when the rod L is removed; but when the rod L is inserted in its recess h and turned so that l is horizontal l raises the lock M by bearing against the ear m, thus placing M in its dotted position, Fig. 4. 100 Further adjustments are obtained by means of set-nuts at each extremity of the bar H, and

by means of a bracket, *i*, which is adjustable along the length of the tie-rod *E*, which is made broad and pierced with holes for this purpose.

What I claim as new, and desire to secure 5 by Letters Patent, is—

1. The combination of the channeled front bed-plate, *F*, with the rear plate, *F'*, frame *A A' B B' B'*, and grate-bars having trunnions supported by said frame.

10 2. The combination, with a grate consisting of a series of pivoted grate-bars, of the swinging bars *K*, connected with the said grate-bars, and the locking-bar *M*, pivoted adjacent to the said bar *K* and having at its lower end a 15 flanged portion adapted to grasp the bar *K* and to swing by gravity into locking contact therewith.

3. In combination with a rocking grate, a bed-plate, *F*, provided with a lug, *u*, the 20 detachable bracket *G*, recessed to receive said lug and provided with legs *g g*, and the swinging bar *K*, suspended from said bracket *G* and connected to said grate.

4. The combination, with a series of connected pivoted grate-bars, of the swinging bar 25 *K*, connected with the said grate-bars and provided with the recess *k*, the detachable handle *L*, having the projection *l*, and the pivoted locking-bar *M*, adapted to be disengaged from the said bar *K* by the said projection. 30

5. The combination, with a furnace-grate consisting of a series of bars provided with projections, of the hanger *G*, detachably secured to the frame of the grate and having arms *g*, provided with a series of holes, the 35 swinging bar *K*, pivotally secured to the said hanger, the connecting-bar *E*, also provided with a series of holes, and the adjustable connecting-rod *H*.

LEONARD M. WOODCOCK.
